(57) **CLAIM**

The ornamental design for a folding knife with multiple blades, as shown and described.

DESCRIPTION

FIG. 1 is a front perspective view of a folding knife with multiple blades showing my new design, wherein the two cutting blades are shown in the open position;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a front perspective view of the folding knife with multiple blades of FIG. 1, wherein the two opener blades are shown in the open position;
FIG. 9 is a front elevation view of the folding knife of FIG. 8;
FIG. 10 is a rear elevation view of the folding knife of FIG. 8;
FIG. 11 is a right elevation view of the folding knife of FIG. 8;
FIG. 12 is a left elevation view of the folding knife of FIG. 8;
FIG. 13 is a top plan view of the folding knife of FIG. 8;
FIG. 14 is a bottom plan view of the folding knife of FIG. 8;
FIG. 15 is a front perspective view of the folding knife with multiple blades of FIG. 1, wherein the saw blade is shown in the open position;
FIG. 16 is a front elevation view of the folding knife of FIG. 15;
FIG. 17 is a rear elevation view of the folding knife of FIG. 15;
FIG. 18 is a right elevation view of the folding knife of FIG. 15;
FIG. 19 is a left elevation view of the folding knife of FIG. 15;
FIG. 20 is a top plan view of the folding knife of FIG. 15;
FIG. 21 is a bottom plan view of the folding knife of FIG. 15;
FIG. 22 is a front perspective view of the folding knife with multiple blades of FIG. 1 in a closed position;
FIG. 23 is a front elevation view of the folding knife of FIG. 22;
FIG. 24 is a rear elevation view of the folding knife of FIG. 22;
FIG. 25 is a right elevation view of the folding knife of FIG. 22;
FIG. 26 is a left elevation view of the folding knife of FIG. 22;
FIG. 27 is a top plan view of the folding knife of FIG. 22; and,
FIG. 28 is a bottom plan view of the folding knife of FIG. 22. The broken lines depict portions of the folding knife with multiple blades in which the design is embodied that are not considered part of the claimed design.
